HENRY C. PEARSON, OF PASADENA, CALIFORNIA

PUSH BALL

Application filed April 1, 1929. Serial No. 351,649.

My invention relates to improvements in the art of play balls, designed to provide an article of manufacture deviating from the common unbroken spherical ball body used for play, and which can be manufactured of any suitable substance other than rubber as well.

The principal object of my invention is to provide a play ball that, unlike the ordinary ball is not thrown or struck at, but which depends for locomotion entirely on a thrust or effort of the player to roll it forward, suitable means for readily accomplishing this being provided as herein shown, the combination furnishing a most unique method for acquiring wholesome exercise, as well as being adaptable to the formation of a game providing healthful pastime for both sexes —old or young,— the diameter of the ball being regulated strictly by the purpose of its use.

At present there are few lawn games of easy and practical application, and with few exceptions, cement or other especially prepared courts or grounds are necessary. One object of this invention is to provide the means for a game that can be played on any lawn or yard or any suitable place without special preparation or change. Furthermore to provide such a means that anyone may play without undue strain or effort and, what is of utmost importance, without the necessity of stooping common to practically every outdoor game.

Ball games particularly for lawns have been of two major types, first, where the ball is rolled by hitting it, as in croquet, and second, where it is released by an underhand throw similar to a low long swing of the arm as in bowling. In my invention neither of these methods is used, the ball rests on the ground and is rolled toward the goal by means of a pusher that gives it a rotary motion from the start. It is not a blow, nor a throw or a sliding force, but a continuous rolling motion from start to finish, and exceedingly effective with very little effort.

I attain this object by means of the combination illustrated in the accompanying drawing, in which—

Figure 1 shows an elevation of a push ball designed to actuate by a ratchet.

Figure 2 is a sectional elevation on line X²—X², Figure 1.

Figure 3 is a side elevation showing a ball in process of being actuated, a ratchet element extending outwardly from a suitable handle member and engaging with a series of taper-pitched teeth in the ball and flush with the circumferential diameter thereof. 55

Similar numerals refer to similar parts throughout the several views.

1 indicates the ball which in its preferred form is solid as is shown, but which may be made in hollow form without departing from 65 the spirit of this invention.

Flush with the circumferential surface of the ball a series of taper-pitched teeth 2 are formed to engage with and properly mesh with teeth 4 on a rack 3 forming a toothed 70 bar extending to a suitable handle member 5.

As a practical article of manufacture, I prefer to construct the ball of a resilient material—preferably rubber, but for certain 75 adaptations, its construction may be more suitably made of wood, cork or other composition or material, but irrespective of the material, always in design and construction such as to make the ball sufficiently heavier 80 in section so that the taper-pitched teeth therein formed will at all times appear upright for engagement with the rotating element and thus assure an instantaneous means of contact with the ball. 85

In its embodiment, the combination provides a most suitable means for the acquirement of healthful exercise, and as a pastime game played in accordance with definite regulations, unquestionably will prove as enjoyable a game as any heretofore evolved, and as a game of skill for propelling the ball in a given direction, will be found quite similar to the requirements of croquet and games of 90 like nature. 95

I am aware that slight modifications may from time to time be made in the details of construction without departing, however, from the scope of the present invention as 100

herein set forth, and as defined in the claims which are appended hereto.

Hence, I do not limit my present invention to the exact description of construction herein disclosed, but what I do claim as new and novel, is:—

1. A ball having a plurality of tapered teeth the tops of which are flush with its surface and adapted to mesh with a toothed rack so as to be put in motion thereby upon application of force to said rack.

2. The combination of a push ball and a push ball engaging member comprising a toothed bar, the teeth of which engage in a series of teeth around the circumferential diameter of said push ball, whereby said push ball is caused to roll upon the application of force against said toothed bar.

HENRY C. PEARSON.
